(57) **CLAIM**

The ornamental design for a bent shaft putter, as shown and described.

DESCRIPTION

FIG. 1 is top front perspective view of a bent shaft of the bent shaft putter of my new design;

FIG. 2 is a top plan view thereof;

FIG. 3 is a right side elevational view thereof, the left side being the mirror image thereof;

FIG. 4 is a front elevational view thereof;

FIG. 5 is a bottom plan view thereof; and,

FIG. 6 is a rear elevational view thereof.

The broken line showing is for illustrative purposes only and forms no part of the claimed design.
